UNITED STATES PATENT OFFICE.

JOHN E. WALSH, OF NEW YORK, N. Y.

DREDGING-MACHINE.

SPECIFICATION forming part of Letters Patent No. 357,880, dated February 15, 1887.

Application filed March 17, 1886. Serial No. 195,510. (No model.)

To all whom it may concern:

Be it known that I, JOHN E. WALSH, a citizen of the United States, and a resident of New York, in the county of New York and State 5 of New York, have invented certain new and useful Improvements in Dredging-Machines, of which the following is a specification.

The object of my invention is to produce an excavator that shall be capable of removing 10 rapidly and economically the material—such as sand or mud—at the bottom of rivers or harbors, as in removing bars or laying foundations. In this respect reference may be had to Letters Patent No. 328,095, granted to me 15 October 13, 1885, upon which invention the present application constitutes an improvement.

In the accompanying drawings, Figure 1 is a sectional view of my invention taken on the 20 line xx in Fig. 3. Fig. 2 is a longitudinal sectional view of my invention on the line yy in Fig. 3. Fig. 3 is a plan view of my invention.

The same letters refer to the same parts throughout.

25 For the above purposes the excavating machinery is mounted upon a base consisting of two vessels or pontons, A, which are secured at the proper distance apart by means of the braces and knees a. These pontons A are 30 strongly built of wood or iron, as may be preferred, and are provided with water-tight compartments a', having valves a'', by means of which the water may be admitted to the compartments a' and the pontons sunk to such a 35 depth as shall insure steadiness to the whole and uniformity to the work. When the pontons are to be moved, the valves a'' are closed and the compartments a' pumped out, when the whole may be readily moved from place 40 to place and adjusted in position by means of the propellers a³ and engines a⁴, assisted by the rudder a⁵.

Upon the top of the pontons A are secured rails or tracks B, upon which travels a 45 frame or bed, C, which frame is provided with rails c c, secured upon its upper part, which are laid in a position at right angles to the rails B. The frame C can be moved upon the rails B from one end of the pontons to the other by 50 means of the windlasses b and ropes b', which

are provided upon the braces a, and the same will also retain the frame C in any position, as desired.

Upon the frame C is placed a carriage, D, which travels upon the rails c c in direction 55 across the line of travel of the frame C upon the rails B, so that by the combined movement of the frame C and the carriage D the carriage D may be moved over the whole area inclosed between the pontons A, or from any 60 part thereof to another part, as may be desired.

The carriage D is made to move upon the frame C by means of windlasses d and ropes d' in manner and effect similar to those used to adjust the frame C on the rails B. Shafting, 65 with screws, gear or racks, or ratchets and hand-spokes, may be used to move either C or D, if preferred.

Within the carriage D is fitted to slide in a vertical direction a frame, E, upon which is 70 secured the hydraulic dredger e, and in this case its motor e', by which it is actuated; but the motor may be located elsewhere, if preferred, and the power transmitted to the dredger e by means of belts and pulleys or shafting and gearing. The dredger e is provided with an excavator, e², which is rotated by means of the shaft e³, driven by the bevel-gear e⁴ and shaft e⁵, which are actuated by the steam-engine F by means of the belt f and pulleys f', as shown. The shafts e³ and e⁵ are 75 provided with grooves or splines e⁶, which, when acted upon by feathers in the bevel-wheel and pulley in the usual manner, give 80 the necessary rotary motion to the shafts without being affected by the motions of the frame E, carriage D, or frame C, as described. 85

The frame E is raised and lowered by means of the racks e⁷ and pinions e⁸, as in the patent referred to. A scale, G, is fixed to the frame 90 E, and an index or pointer, g, is fixed upon the frame D in such a relative position as to at all times indicate the depth at which the excavator may be located below the ponton A. A similar scale, g', is affixed to the hulk of the 95 ponton A, so that by properly combining the figures shown upon the two scales g' and G the depth of the excavator below the surface of the water may at all times be known, thus enabling the attainment of great accuracy in re- 100

ducing the excavation to a uniform level surface or to make such variations therein as may be desirable.

Upon the carriage D is fixed a swinging derrick or crane, H, having arms h and traveling carriages h' , arranged in the usual manner. From the carriages h' are suspended the chutes or troughs h^2 , which conduct the mud as excavated from the discharge-pipe e' of the dredger to e to the scows I, which are to convey the same to its destination.

The arrangement described above facilitates the proper adjustment of the chutes h^2 to correspond with any change in the relative position 15 of the dredge e and receiving scows I.

The receiving-scows I are made in the form of tight pontons provided with bulwarks or sides i , which retain the load upon the deck of the scow. The deck i' is made with an 20 inclination, either double, as shown, or single, if preferred, being lowest at the sides, so that upon opening the valves or doors i^2 , provided for that purpose, the cargo of the scow will discharge itself by reason of its own gravity. 25 The valves i^2 are closed and held by means of the chains i^3 and windlass-shaft i^4 . The scows I are also provided with propellers i^5 and engines i^6 , by means of which they can be moved independently of the pontons A.

30 Swinging booms or struts K, having joints k at each end, which allow them to swing in every direction, are secured to the pontons A, and also to the scows or pontons I, keeping the two at a proper distance apart to allow of 35 some independent vertical movement of I, as when excavating in rough water; or, if the ponton A is resting upon the bottom, the pontons I may rise and fall to the tide without inter-

ferring in any way with the work. Spuds may also be employed, as shown at N, to steady the whole in position.

Having thus described my invention, I claim and desire to secure by Letters Patent—

1. In combination with a dredging mechanism, the double hulk consisting of two pontons, A A, each having compartments a' and valves a^2 , and provided with rails B B, the braces $a a$, securing the pontons together, and windlasses $b b$, mounted on said braces, by means of which the dredging mechanism may 45 be moved upon the rails B B, substantially as and for the purposes herein shown and set forth.

2. The combination of the derrick H with the frame C, carrying the dredging mechanism, and the chutes h^2 , substantially as herein shown and described.

3. The combination of the double hulk having a scale, g' , by which the height of its deck above the surface of the water is shown, with a 60 dredging mechanism having a scale, G, showing the depth below the deck of the hulk at which it may be acting, as herein shown and described.

4. The swinging booms K, connected to the 65 hulk and also to the receiving-pontons I by means of the joints k , when constructed and operated as and for the purposes herein shown and set forth.

Signed at New York, in the county of New 70 York and State of New York, this 13th day of March, A. D. 1886.

JOHN E. WALSH.
